DESIGN FOR A PLANE

Rudolph Müller, Elizabeth, N. J.

Application March 26, 1942, Serial No. 106,334

Term of patent 14 years

To all whom it may concern:

Be it known that I, Rudolph Müller, a citizen of the United States, residing at Elizabeth, in the county of Union and State of New Jersey, have invented a new, original, and ornamental Design for a Plane, of which the following is a specification, reference being had to the accompanying drawing, forming part thereof, in which

Fig. 1 is a side elevational view of a plane showing my new design;

Fig. 2 is a top plan view;

Fig. 3 is a front elevational view, and

Fig. 4 is a rear elevational view.

I claim:

The ornamental design for a plane, as shown.

RUDOLPH MÜLLER.
